UNITED STATES PATENT OFFICE.

JAMES H. PERRIN, OF LOS ANGELES, CALIFORNIA.

COLLAPSIBLE STOOL CONCEALED WITHIN A WALKING-STICK.

1,166,386.

Specification of Letters Patent.

Patented Dec. 28, 1915.

Application filed March 31, 1913, Serial No. 757,730. Renewed April 26, 1915. Serial No. 24,171.

To all whom it may concern:

Be it known that I, JAMES H. PERRIN, a citizen of the United States, and residing in the city of Los Angeles, county of Los Angeles, and State of California, have invented 5 a new and useful Improvement in a Collapsible Stool Concealed Within a Walking-Stick, of which the following is a specification.

10 This invention relates to foldable stools, and the principal object is to provide a stool that will fold into a small compass and be concealed within a walking stick.

It is also an object to provide a foldable 15 stool with a plurality of hinged arms and legs which are operatively connected by means of a central reciprocating rod.

It is a further object to provide a folding 20 stool with a flexible seat which can be readily disengaged from the seat supporting arms and rolled or folded into a small compass, and be concealed within a walking stick together with the rest of the structure.

More specifically in the drawings accompanying this specification—Figure 1 is a 25 side elevation showing the complete stool set up ready for use. Fig. 2 is a view taken from the same side showing the legs folded by extending the central rod outwardly. Fig. 3 is a similar elevation showing the device completely folded. Fig. 4 is an enlarged detail of the body portion and the hinged connections. Fig. 5 is a section on the line 5—5 of Fig. 3. Fig. 6 is an enlarged 35 detail of the head of the rod. Fig. 7 is a detail of the hinging of the arms to the body portion. Fig. 8 is an enlarged detail showing how the leg braces are slidably connected to the legs.

40 More specifically in the drawings, 10 designates the body portion consisting of a substantially cylindrical member having a central longitudinal bore therethrough to form a sliding engagement with the reciprocating rod 11, which is provided with a head 12, and a foot bracket 14.

In the drawings four legs designated 15 are shown to the stool, these being preferably formed of sheet metal, having a curved 45 outer face 16 and parallel sides 17, this face and sides being preferably closed in the bottom to form a foot 18. Suitable bores are carried through the sides 17 of the leg adjacent their upper ends, through which are carried pivot pins 19, which are carried 55 through lugs 20 depending from the body

portion 10. These lugs are so disposed below the shoulders 21 formed upon the body portion of the terminal edge 22 that the face butts against this shoulder, acting as a 60 stop when the legs are extended in operative position.

The arms 24 are preferably formed of metal of similar cross section, as the legs, are preferably of less length, and are hinged 65 to lugs 34 on the upper portion of the body member by means of pivot pins 25, recesses being cut in the upper portion of the body, against which the lower and inner edges of the arms abut to form limiting stops for 70 said arms. The outer and upper ends of the arms are preferably formed or have brazed thereto a head 26 which engages with suitable eyes in the flexible square of fabric 75 27 adapted to form the seat for the stool, and assist the stops for the arms in preventing their extension beyond the proper point.

The rod 11 previously mentioned as reciprocatingly mounted within the body 10, is provided to draw each one of the hinged 80 limbs in proper relation when the stool is folded, and to accomplish this a plurality of straps hinged to the rod, are connected to each limb of the stool. The upper straps 30 are hinged to the head of the rod by means 85 of pins 31, one strap extending to each arm 24 and hinged thereto by a pin 32.

The lower straps 33 are pivotally connected to the foot 14 on the rod by means of pins 44, and these straps at their outer ends are pivotally secured by means of a hinged pin 35 to a strap 36, which is slidably mounted in engagement with the lower portion of the leg, being held in this relation by means of a pin 37. The lower end of this 90 strap 36 is off-set and provided with a toe 38 which is adapted to rest upon the foot 18 of the leg when the legs are extended, the foot being built slightly cup-shaped to receive the toe 38 to limit the downward 95 movement of the strap 36 and form a support for the latter.

The stool is shown in folded relation and inclosed within the tubular structure 40 of the walking stick, the face 16 of the limbs being so formed that they closely fit within the inner periphery of the walking stick.

The operation of the device will be readily understood from the drawings, the straps 33 forming a double function of not only drawing the legs together to fold the stool, but when extended, limit the distance the legs

are extended, and they also act as braces to prevent the collapse of the stool should the stops on the shoulders fail. The extension of these straps is necessary so that in the positive movement of drawing in the legs, when this is accomplished, the arms are still extended in the position shown in Fig. 2, further extension of the rod sliding the straps 36 in relation to the pin 37 and positively drawing in the arms 24.

What I claim is:

1. In a foldable stool having a sleeve, a plurality of legs pivotally secured to one end of the sleeve, a plurality of arms pivotally secured to the opposite end of the sleeve, a reciprocating rod mounted to slide in the sleeve, and links connecting the upper end of said rod to the arms, slidable members on the legs, and links connecting said slid-
able members to the lower end of the rod.
2. In a foldable stool having a sleeve, a plurality of legs pivotally secured to one end of the sleeve, a plurality of arms pivotally secured to the opposite end of the sleeve, a reciprocating rod mounted to slide in the sleeve, and links connecting the upper end of said rod to the arms, a foot bracket

on the lower end of the rod, slidable members on the legs, links connecting said members to the foot bracket, means on the legs 30 for limiting the movement of the slidable members.

3. A folding stool, comprising a sleeve, a series of arms pivoted to the upper end of the sleeve, a rod slidable in the sleeve, links connecting the upper end of the rod with the arms, a plurality of legs pivoted to the lower end of the sleeve formed with channels on their inner faces, an inturned foot on the lower end of each leg, slidable members 40 arranged in the channels of the legs, connections between the rod and said slidable members, whereby the latter will be caused to bear upon the feet when the legs are spread and the rod is in its lowermost position.

In witness that I claim the foregoing I have hereunto subscribed my name this 14th day of March, 1913.

JAS. H. PERRIN.
